(57) **CLAIM**

We claim the ornamental design for a combined nursing bottle and formula mixer, as shown and described.

DESCRIPTION

FIG. 1 is a perspective view of a combined nursing bottle and formula mixer showing our new design;
FIG. 2 is a front elevational view thereof;
FIG. 3 is a rear elevational view thereof;
FIG. 4 is a left side elevational view thereof, the right side elevational view being a mirror image thereof; and
FIG. 5 is a top plan view thereof; and,
FIG. 6 is a bottom plan view thereof.
